CIRCUIT CLOSER FOR KNITTING MACHINES

Michael Wachsman, Brooklyn, N. Y.

Application May 5, 1937, Serial No. 140,839

3 Claims. (Cl. 66—163)

This invention relates to improvements in electric circuit closers for knitting machines of the type disclosed in the Reissue Patent 19,069, February 6, 1934, and in the Patent 1,784,560, December 9, 1930, to Jacob Wachsman. Generally speaking such circuit closers include a knot detector member and an end detector member which are combined or used separately for the purposes of closing an electric circuit when a knot occurs in the yarn or when the yarn breaks or runs out. The closing of the circuit in turn actuates the stop mechanism per se which is a part of the knitting machines. Such detector units, their function and operation are well known in the art.

The object of my invention is to improve the detector units generally with a view of more efficient operation and greater range of use. One object of the invention is to provide detector members in the form of porcelain disks or disk like members with the advantages of greater cleanliness, better appearance and greater adaptability for use both as knot detectors and end detectors and as tension devices. Another object is to provide end detector units which may be mounted in such a position and so operated that electrical conducting rings and like parts, heretofore thought necessary, are no longer required. Other objects will appear as this specification proceeds.

Accordingly my invention is embodied in electric circuit closers, including tension devices, which are arranged and constructed as herein-after set forth and as illustrated in the accompanying drawings in which,

Fig. 1 is a diagrammatic view of a detector unit and bobbin supporting device adapted to be attached to a circular knitting machine.

Fig. 2 is a plan view of an end detector unit and yarn tensioning device shown in Fig. 1.

Fig. 3 is a side view thereof.

Fig. 4 is an enlarged end view of a combined knot and end detector unit.

Fig. 5 is a face view looking from the left in Fig. 4 with parts removed.

Figs. 6 and 7 are sectional views taken on the lines 6—6 and 7—7 of Fig. 5.

Fig. 8 is a view of a modified end detector disk or member.

The device shown in Fig. 1 is sometimes called a stop motion top because it is attached at the top of or above a circular knitting machine. The device includes a central rotating shaft 1 which by any suitable well known means is attached to the central rotating shaft or part of a knitting

machine. Such connecting means are not shown, being well known in the art. The shaft 1 carries four sets of radial arms 2, 3, 4 and 5 for the support of circuit closer units 6, end detector units 7 and the yarn bobbins 8 as shown. Each unit 5 includes a contact box which comprises a box 10 with a fixed circuit terminal 11. Inside the box there are contact springs connected to the terminal 11. The springs are adapted to be contacted by contact heels secured to the knot detector 10 and to the end detector members so that when a knot occurs or the yarn breaks contact is made to close the circuit.

In Fig. 2 the contact spring 12 is a simple spring to be contacted by the contact heel 13. In Figs. 15 5, 6, and 7 the contact spring is formed with two fingers 14 and 15 to be contacted by contact heels 16 and 17 respectively.

Referring now to Figs. 1, 2, and 3 the end detector units 7 each consist of the contact box 10 20 with terminal 11 and contact spring 12. The contact heel 13 is fast on a sleeve 25 carried by a detector shaft 26 held in fixed axial relation to box 10 by a collar 27. The sleeve carries a detector disk 28 which is preferably a circular porcelain member provided with a slot 29. Below the disk 28 there is an eye plate disk 30 secured to the shaft 26 and provided with a thread opening 31. Above the disk 28 there is another disk 32 secured to the shaft 26. The disk 32 has a slot 30 33 in the opposite direction to the aforesaid slot 29. The thread opening 31 permits free passage of the yarn except when a knot or other obstruction occurs in the yarn which cannot pass through said opening.

The shaft 26 is held in nonrotatable relation to the box by a collar 34. The sleeve 25 is loose on the shaft and a spring 35 in the box urges the contact heel 13 into contact with the spring 12. The yarn 40 passes from the bobbin 8 up through the yarn opening 31 and is then passed through the slots 29 and 33 and up to the units 6. The arrangement is such that while the thread passes through the three disks 31, 28 and 32 the middle disk 28 is prevented by the thread from turning clockwise in Fig. 2 so far that the contact heel 13 can engage the spring 12 to close the circuit. When however, the thread breaks above or below the unit 7, the thread no longer offers any resistance to the turning of the disk 28. The latter 45 is then rotated by the pull of the spring 35 so that the heel 13 contacts the spring 12 to close the circuit as will be understood. On the other hand, while the thread passes through the three porcelain disks, the disk 28 functions as a ten- 50 55

sion member because the spring 35 tends to pull the thread out of alignment with the upper and lower openings 31 and 33.

The upper and lower detector units 7 are alike and self-containing to close the circuit. The upper units 7 are mounted on the arms 3 as shown in Fig. 1 and the lower units 7 are mounted on the arms at an angle to accommodate the thread as it comes down from an eye plate 41 and before it passes to the knitting mechanism, not shown.

It is understood of course that all the contact boxes 19 are connected by wires 42 to a magnet 43 and battery 44. When the circuit is closed in any of the boxes the magnet is energized to actuate the lever 45 or other member which in turn operates the stop control of the knitting machine.

Referring now to Figs. 4-7 which illustrate the combined knot and end detector units 6, see Fig. 1, the contact box 19 in Fig. 5 is shown with its cover removed. It supports a rotatable shaft 53 to which the contact heel 17 inside the box is fixed. Outside the box the shaft carries an end detector disk 51 by means of a nipple 55. The disk 51 is directly behind the knot detector disk 52 in Fig. 4. The disk 52 is carried by a nipple 56 which rotates on the shaft 53. A second knot detector disk 53 is also supported on the shaft 53 by means of a nipple 54. The two nipples 55 and 54 are connected by a wire yoke 57 so that the two knot detector disks 52 and 53 turn together on the shaft 53. The nipple 54 extends within the box 19 and carries the contact heel 16. All three porcelain disks 52, 51 and 53 have yarn enclosure openings 58 and yarn supporting noses 59.

In operation the yarn 40 lies upon the disk noses 59 of the three disks. The two knot detector disks are held in upper normal circuit open position by the spring 35 which pulls a stop 60 in the sleeve 54 against the wall of the box. When a knot occurs the yarn can no longer pass through the thread opening 31 in the eye plate disk 39 and run upwards to the disks and over the yarn supporting noses 59. The pull upon the yarn from the needle mechanism continues however and the disks are therefore caused to rotate anticlockwise and the sleeve contact 16 then engages the spring 14 to close the circuit. The yarn slips off the disk noses and the spring 35 then pulls the knot detector disks back to normal position while the end detector disk is pulled upwards in clockwise direction by a second spring 61. The contact 17 then also engages the spring 15 but this is of no consequence the circuit already having been closed.

When the thread breaks or runs out the end detector disk 51 is immediately moved into circuit closing position by the spring 61 to close the circuit and stop the machine. The nipples 54, 55, and 56 are squared on the outside as shown to fit corresponding square openings in the porcelain disks. This makes for easy attachment.

During operation the thread travels upward up over the three noses in the disks and then down as shown in Fig. 1. The knot detector disks are held relatively immovable by the spring 35 although the spring is adjusted so as to avoid complete rigidity and the disks will yield to some extent to the pull of the thread. The end detector disk is constantly urged in a clockwise

direction in Fig. 4 by its spring 61 and tends to lift the thread off the knot detector disks to prevent the thread from jumping off and to take up slacks. By using a single design for the disk, uniformity in manufacture, weight and the like is assured. Still another factor is that in threading the disks the yarn is simply dropped upon the front round surfaces or portions 62 and then slides easily downward into position.

Fig. 8 illustrates a modification in which the end detector disk 51 is provided with an adjustable weight 63 as a substitute for the spring 61. The springs in all the boxes are adjustable by screws 64.

It will be seen therefore that this invention provides detector units and tension devices in which the members under the control of the travelling thread may be made very much alike in the form of porcelain disk members which require but a few forms for casting or making. Each unit is easy to thread and in only one instance it is necessary to thread the end of the yarn through an opening namely in the eye plate 39. The two disks 23 and 32 in the units 7 are threaded by moving the thread sidewise into the slots 29 and 33. The detector units 6 are threaded by dropping the thread on the disks.

Although the invention has been disclosed in its preferred form it will be understood that it is susceptible of modification and changes without departure from the scope of the appended claims.

I claim:

1. A circuit closer unit for knitting machines under the control of a travelling thread comprising a housing, electric circuit terminal fingers within the housing, a plurality of contact heels within the housing, three thread supporting porcelain disks outside the housing, means operatively connecting the middle disk with one of the contact heels, means operatively connecting the other two disks with another contact heel whereby when said disks are moved by an abnormal operation of the thread, the said contact heels are operated to contact the said terminal fingers to close the electric circuit.

2. A circuit closer unit for knitting machines under the control of a travelling thread comprising a housing, electric circuit terminal fingers within the housing, a shaft rotatably supported on the housing and having a contact heel within the same adapted to contact one of said terminal fingers, a disk-shaped thread supporting member secured to the shaft outside the housing, a disk-shaped thread supporting member on each side of the said first disk-shaped thread supporting member and supported to rotate about the same shaft and means operatively connecting the said two disk-shaped members to another contact heel whereby when one or more of said disk-shaped members are rotated by an abnormal operation of the thread supported thereby, one or both of said contact heels are operated to contact their respective terminal fingers.

3. In a circuit closer unit for knitting machines under the control of a travelling thread, means for closing the electric circuit when the thread breaks or a knot occurs therein, said means including as an article of manufacture a porcelain disk having a thread enclosing opening and a thread supporting nose, and an adjustably supported counterweight in said disk in diametrically opposed relation to the said opening.

MICHAEL WACHSMAN.
